RIP STRIP KEY AND ATTACHING MEANS
FOR CONTAINERSJames H. O'Neil, Syracuse, N. Y., assignor to
Continental Can Company, Inc., New York,
N. Y., a corporation of New York

Application March 18, 1933, Serial No. 661,597

2 Claims. (Cl. 220—52)

The invention has to do with new and useful improvements in a key for removing the tearing strip of an easy opening container and the attaching means, whereby said key is secured to 5 the container.

An object of the invention is to provide a key attaching means whereby the key may be attached to the container end within the depressed portion thereof through a yielding gripping contact with the opposed walls of an arcuate recess in the container end.

A further object of the invention is to provide 15 a key attaching means of the above type, wherein a portion of the handle of the key makes a yielding three-point contact with the opposed walls of the recess.

In the drawing:

Fig. 1 is a plan view of a container having the key attached thereto by the improved key attaching means.

Fig. 2 is a vertical sectional view of the same.

Fig. 3 is a view on an enlarged scale and in section through the handle of the key for showing the three-point gripping contact between the key 25 and the arcuate recess in the container end.

Fig. 4 is a view similar to Fig. 1 but showing a slightly modified form of key.

In carrying out the invention, the key for removing the tearing strip is preferably formed of 30 wire bent upon itself to provide a shank having a slot adapted to be placed over the end of the rip strip so that it may be rolled onto the shank of the key. The wire forming the shank is bent laterally and thence into loop form to provide a 35 handle. In a preferred form of the invention, the ends of the wire are substantially in contact at the center of the outer member of the handle.

This outer member of the handle is offset from 40 the plane of the shank so that it may be inserted in a recess in the container end. The recess may be formed all the way around the end in a complete circle or for a short distance. It is essential, however, that it should be of sufficient length to completely house the outer member of the handle portion of the key. This outer member of the 45 handle portion is so shaped that a three-point contact is made with the side walls of the recess.

Two points of contact at spaced distances are made with the outer wall of the recess and the 50 central portion of the outer handle member contacts with the inner wall of the recess midway between said points of contact with the outer wall. This enables the handle member to have a yielding but firm frictional grip with the arcuate shaped recess in the container end.

Referring more in detail to the drawing, the container as shown includes a body portion 1, having score lines 2 and 3 which are spaced from each other so as to set off a tearing strip therebetween, which tearing strip has a tongue 5 attached thereto, on which a key is placed for rolling the tearing strip onto the key and rupturing the metal. The container end or cover 5 is secured to the container by a seam 6, which may be of any desired character. The container end 60 may be of any desired shape, but it is essential that it shall be provided with an arcuate recess 7, having opposed side walls 8 and 9. The key is preferably formed from a spring wire which is bent upon itself so as to provide the shank 65 portions 10 and 11 with a slot 12 therebetween. The tongue of the tearing strip is inserted in this slot and when the key is turned, it will cause the shank portions to grip the tongue and roll the same so as to rupture the metal. The shank portion 11 is bent laterally as indicated at 13 and is then extended substantially radially of the container as indicated at 14, where it is again bent laterally substantially at right angles of the plane of the key, as indicated at 15. The wire is then 70 bent substantially at right angles to this lateral portion 15, as indicated at 16. The shank portion 10 is bent laterally in the opposite direction as indicated at 17 and thence in substantially radial direction as indicated at 18, and thence 75 laterally out of the plane of the key and inwardly as indicated at 19. The ends of the portions 16 and 19 as shown in Figs. 1 and 2, substantially meet centrally of the shank of the key. They may be joined, but it is preferable to separate the 80 ends slightly for reasons which will be presently stated.

The key thus formed has a handle portion which projects laterally from the shank and which may be used for forcibly turning the shank portion 95 to wind the tearing strip thereon. The outer members of this handle portion indicated at 16 and 19 are substantially in alignment. This portion of the key is forced into the arcuate recess 7. It will make a three-point gripping contact 100 with the side walls of the recess. The portions 15 of the key will contact with the outer wall of the recess at the points *a* and *b*, which are widely spaced from each other. The inner ends of the members 16 and 19 will contact with the inner 105 wall of the recess in the region indicated at *c*. This may be considered a single point of contact, although when the ends are spaced, they are in reality two points of contact. The relatively straight handle portion of the key is forced into 110

this arcuate groove and is so dimensioned that it will make these three points of contact and the ends of the members 16 and 19 will yield to permit the forcing of this handle portion into the recess. The walls of the recess are substantially vertical and therefore the key will be firmly gripped by said walls. By lifting the key it can be readily sprung out of the recess and can be replaced if desired.

10 The recess 7 as shown in the drawing, extends all the way around the end forming a complete circle. This has its advantages as when the key is attached to the end it does not have to be placed in any particular radial position relative to the 15 end in order to be pressed into the groove. The recess, however, may be only of sufficient length to receive the handle portion of the key. The key may be attached to the end before the end is attached to the container, or it may be attached to 20 the end after the end has been attached to the container. All that is necessary is to place the key in proper position on the end to forcibly spring the handle portion thereof into the arcuate recess so that the key will have gripping contact with 25 the walls of the recess.

In Fig. 4 of the drawing, the container is of the same construction, but the key has been structurally modified. The shank portion 10 of the key terminates at the point 20. The shank portion 30 of the key is bent laterally at 13 and thence substantially radially as at 14 and thence again laterally and out of the plane of the key and again laterally as indicated at 21, which handle member 21 extends all the way across the central line of 35 the key and to the other side of the handle portion of the key. The wire forming the key is then bent back to the plane of the key and substantially radially as indicated at 22 and thence laterally as indicated at 23, so that the end thereof terminates 40 close to the end 20 and may be attached thereto if desired. The laterally extended portion of the handle contacts with the outer wall of the recess at the points *a* and *b*, and the central portion of this member 21 contacts with the inner 45 wall of the recess at the point *c*. The manner

whereby the key is yieldingly and frictionally held in the recess is precisely the same as shown in Figs. 1 to 3. This member 21 will yield so that it may be forced into this arcuate groove, making the three-point contact referred to above.

It is obvious that the key may be otherwise shaped than shown and that some other portion of the key may have gripping contact with the container. The essential feature resides in a construction whereby a portion of the key will make a three-point contact with an arcuate recess in the container end.

Having thus fully described the invention, what I claim as new and desire to secure by Letters Patent is:

1. The combination with a container having a tearing strip and an arcuate groove in the container end adjacent the double seam and concentric thereto, a key adapted to engage said tearing strip, said key being of spring wire bent upon itself to form a shank and a handle, said handle having portions thereof bent at substantially right angles to the plane of the shank and forming contact points adapted to engage one wall of said arcuate slot, said handle having a yielding portion 100 disposed between said contact points and adapted to engage the other wall of said arcuate slot for holding said key in engagement with the container.

2. The combination with a container having a 105 tearing strip and an arcuate groove in the container end adjacent the double seam and concentric thereto, a key adapted to engage said tearing strip, said key being of spring wire bent upon itself to form a shank and a handle, said handle 110 having portions thereof bent at substantially right angles to the plane of the shank and forming contact points adapted to engage one wall of said arcuate slot, said handle having yielding portions projecting toward each other and spaced so as 115 to yield independently, said yielding members being adapted to contact with the other wall of said arcuate slot for holding said key on said container.
